Application April 20, 1940, Serial No. 330,654

13 Claims. (Cl. 200—152)

This invention relates to mercury switches of the metal envelope type, and is directed more particularly to an improvement in such switches over the type shown in the patent to Paul S. Bear, No. 2,132,921, issued October 11, 1938.

In previous types of mercury switches of the metal envelope type in which a ceramic insert is provided at one end for supporting an electrode in insulated relation to the metal shell it has sometimes been found desirable to provide for retaining a body of mercury in contact with the electrode in order to secure a mercury to mercury contact within the envelope. However, in all of the constructions with which we are familiar, it appears that, under certain conditions, the apparent mercury to mercury contact is in reality a metal to mercury contact due to the fact that rapid tilting of the switch causes the movable body of mercury to impinge directly upon the electrode face, thus producing arcing between the metal and the mercury. A metal to mercury contact switch of this type, according to tests we have conducted, has only about one-fourth of the normal life of a switch embodying a mercury to mercury contact.

The present invention has for its primary object the provision of a switch construction in which the retained and movable bodies of mercury are in nearly equalized volume so that in effect a double run of the mercury is provided upon tilting of the switch in either direction. The term "double run" mercury is coined from the fact that the mercury now runs in two directions simultaneously at the instant of make or break in the switch. Switches of the type heretofore known might be called single run switches, since the retained body of mercury was held substantially stationary and the balance of the mercury was caused to part therefrom and run down an inclined spillway for breaking the circuit.

In designing the structure so that mercury to mercury contact is insured, about 25% to 50% of the total mercury volume should be retained in contact with the fixed electrode and the remaining portion of the mercury allowed to move upon tilting of the switch in contact with the switch envelope. With such a construction providing a relatively large well for the retained body of mercury, upon tilting of the switch toward switch closed position the retained body moves simultaneously with the movable body and blanks off the electrode face so that the leading edge of the movable body is prevented from contacting directly with the electrode but

instead, contacts the moving portion of the retained body which at this time overlies the electrode face. As a result, positive mercury to mercury contact is provided in the switch.

5 Similarly, when the switch is in switch closed position, tilting of the switch toward switch open position results in both bodies of mercury moving simultaneously away from the switch closed position with the two bodies being separated over the ceramic barrier at a point removed from the electrode face, one of the bodies running down into the well adjacent the electrode, while the other body moves down into the main portion of the switch envelope. Due to this simultaneous movement of both bodies in both making and breaking operations, it is apparent that a snap action or increased rapidity of contact will be provided as well as an increased rate of separation, since velocities of the two bodies are 10 cumulative. As a result, even if the switch is used in response to a slow moving actuator such as a thermostat or the like, the velocities of the body due to the double run feature will prevent any appreciable arcing, either upon making or 15 breaking of contact.

By providing the increased volume of mercury in the retaining well approximately one-fourth of the total mercury volume in the switch, and in some cases being substantially one-half of this 20 volume, a cooler operating switch is provided.

Still another feature of the present invention is to design a switch construction in which the point of making and breaking of the circuit is produced over a ceramic or insulating surface 25 appreciably removed from the electrode face, which insures a cool operating switch and prevents any possibility of arcing on the adjacent metal.

Still another feature of the present invention 30 is the design of the structure so as to provide for rapid dissipation of heat from the interior of the switch. This may be produced by forming the envelope in such manner that air circulation is provided adjacent all portions of the ceramic 35 and by insuring that the point at which the two bodies of mercury make and break contact is removed from both electrodes.

Another feature involved in the present design 40 is the provision of a ceramic structure including a relatively large undercut beneath the cutting edge of the ceramic, this undercut forming a relatively large well for receiving an appreciable 45 volume of mercury, and also being formed in part by a skirted portion of the electrode to increase the area of contact between the body of

mercury and the electrode, thereby reducing the internal resistance through the switch.

Still another feature of the present invention is the provision of a ceramic designed with due regard for the fact that mercury bodies retain their stability only when confined within an opening of $\frac{7}{32}$ " or less. Employing this characteristic, the ceramic in one form of the present invention is so designed as to provide a substantially fixed retained body of mercury in contact with the electrode, but so arranged that the movable body of mercury will at no time have any opportunity to contact the face of the electrode directly, but will contact stabilized portions of the retained body prior to moving into proximity to the electrode. As a result, such a switch has a very stable action and can be used for high speed operation without any danger of double or secondary contacts. In connection with this, the area of contact between the retained body and the electrode is materially increased to insure low internal resistance, and consequently cool operation of the switch.

Another advantage derived by the present invention resides in the forming of an electrode structure in which the retained body of mercury is in contact with an appreciable area thereof but the electrode face is shielded against any possible contact from the movable body of mercury, positively insuring a mercury to mercury contact. This shielding may be produced by covering the radial portion of the electrode which faces the opening in the ceramic with a suitable insulating medium or in any other suitable manner.

Still another advantage secured by the present invention is the design of a switch having a straight cylindrical bore in the ceramic and provided with a radially extending shoulder or abutment at the envelope end of this bore whereby the movable body builds up and substantially breaks across the space into contact with the retained body. This provides a rapid contact insuring little or no arcing between the two bodies even with relatively slow tilting of the switch, since the surface tension of the mercury prevents the contact until a sufficient head has been built up by the dam to insure the movable mercury breaking rapidly across the ceramic surface.

Still another object of the present invention is to provide a switch construction in which the face of the electrode is provided with a baffle disc composed of a metal which is arc-resistant and which may be of the group comprising tungsten, molybdenum or tantalum. By facing the iron electrode face with a metal having a far higher melting point, lower resistance and higher conductivity than that of iron, the iron disc is protected, and at the same time the conductivity through the switch is greatly increased.

The invention also provides certain other advantages incident to construction and economies provided by simplified design, and these and other objects and advantages will be more apparent to those skilled in the art from the following detailed description which, taken in conjunction with the accompanying drawings, will disclose particular constructions and operation of preferred forms of the present invention.

In the drawings:

Figure 1 is a vertical sectional view through one form of switch embodying the present invention;

Figure 2 is a corresponding view of a modi-

fied structure having the electrode face shielded against contact by the movable body of mercury;

Figures 3 to 6, inclusive, are corresponding views of a further modified form of switch in various operating positions illustrating the double run characteristics provided by the enlarged volume of mercury retained in contact with the electrode;

Figure 15 is a sectional view through a still further modified form of switch.

35 Referring now in detail to the drawings, in Figure 1 we have disclosed a switch envelope indicated generally at 5 having a relatively elongated tubular portion 6 closed at one end, as indicated at 7, and provided with a reversely turned annular flange portion 8 spaced from the external periphery of the tubular portion 6 by the gap 9.

From the flange portion 8 the envelope has 40 a radially and axially directed flanged or shouldered portion 10 terminating at its outer edge in the enlarged cylindrical flange 12. This switch envelope may be formed by drawing or the like, or in any other suitable manner, and preferably, is subjected to a hydrogen annealing process to 45 drive out occluded gases and burn off impurities before the ceramic 13 is inserted into the flanged end thereof. The ceramic 13 is provided with a shoulder portion 14 abutting against the radial flange 10 and provided with an annular 50 groove 15 in the face thereof in which is inserted a resilient sealing ring 16, which ring is compressed against the surface of the flange 10 to provide an effective seal preventing leakage between the external surface of the ceramic and the internal surface of the envelope.

The ceramic 13 is provided with radially spaced 55 annular grooves 17 and 18 spaced apart by an annular axially extending partition or wall 19, the grooves 17 and 18 forming a series of undercutts beneath the radially inwardly extending flange portion 20 of the ceramic which is bored, as indicated at 22, to provide an opening from the tubular portion 6 of the envelope into the outer end of the ceramic. The annular groove 70 17 in the ceramic is counterbored to provide a radial shoulder 23 against which is seated the forward edge of the cylindrical flange 24 of a metal electrode 25 disposed in the counterbore and centered with respect to the ceramic thereby. The electrode 25 closes the outer end of the

ceramic and, as noted, is spaced an appreciable distance rearwardly of the bore 22 of the ceramic. The electrode 25 is of disc-like form having the projecting flange 24 forming a cup-shaped recess with the outer end of the ceramic. The electrode is provided with an axially outwardly directed shank 26 adapted to be connected to any suitable current source.

Suitable resilient sealing means 27 engages the radial outer face of the electrode 25 about the shank 26, and is provided with an axially extending peripheral skirt 28 radially overlapping the outer end of the electrode, and also the shouldered portion 29 of the ceramic. The seal 27 is compressed into sealing engagement between the electrode, ceramic and flange 12 by means of an insulating compression member 30 urged into compressive engagement with the seal by means of the retaining flange or ring 32 and the spun-over edge 33 of the envelope. Preferably, the compression member 30 is provided with a cylindrical axial extension 34 forming an insulating separator between the metal retaining ring 32 and the electrode shank to prevent any possibility of flash-over therebetween. The compression produced by spinning over the end 33 of the envelope also serves to compress the sealing ring 16 providing an additional seal adjacent the front or inner portion of the ceramic.

After the ceramic and electrode have been sealed in position, as described above, the envelope is partially filled with mercury through the tubulation 35 at the closed end 1 of the tubular portion 6 of the envelope. The volume of mercury introduced is sufficient to form the retained body 36 and the movable body 37 separated by the radially inwardly flanged portion 20 of the ceramic. It will be apparent that the retained body 36 is of appreciable volume as compared with the body 37 since it fills the lower portions of both of the annular grooves 17 and 18, and also the annular space between the electrode face and the flange 20 of the ceramic. It will be noted that this body of mercury lies in contact with both the electrode face and also with the flange 24 of the electrode for an appreciable part of the circumference thereof, thus providing ample contact area to insure low conductivity therebetween. After the mercury bodies have been introduced into the envelope, the tubulation 35 is subjected to a vacuum for exhausting all air or other gases which may have been trapped in the envelope, and the interior of the envelope is then subjected to a hydrogen atmosphere under pressure. While maintaining the tubulation connected to a source of hydrogen under pressure, the tubulation 35 is pinched flat, as indicated at 38, and this flattened portion is then welded, sealing off the interior of the envelope with the hydrogen retained under pressure therein.

The switch of Figure 1 is adapted for operation by tilting movement, and it will be at once apparent that upon tilting the switch from the position shown in a counter-clockwise direction, the body of mercury 36 being of an appreciable volume will flow upwardly over the face of the electrode 25 at the same time that the body of mercury 37 starts to build up a head against the opposite side of the flange 20. This double movement of the mercury insures, first, the protection of the electrode face against any possibility of a mercury arc, and, secondary, a movement of the two bodies of mercury toward the bore 22, which increases the rapidity of action

so that as the body of mercury 37 breaks over the lower defining edge of this bore it moves into direct contact with the body of mercury 36, positively insuring a mercury to mercury contact in which the arc will occur somewhere about the defining edge of the bore 22. Similarly, when the switch of Figure 1 is tilted in a clockwise direction from a switch closed position, the two bodies of mercury will both begin to move, the body 36 moving back into the grooves 17 and 18 of the ceramic and downwardly with respect to the bore 22 while the body 37 moves outwardly through the bore 22 toward the closed end 1 of the envelope. Thus, both bodies of mercury are simultaneously moving away from the defining edge of the bore 22, and consequently breaking of the circuit will be effected at this defining edge, which is spaced an appreciable distance from the electrode face. Thus, any arcing produced by the breaking of the switch will have no effect upon the electrode face. Similarly, the body of mercury 37 will protect the tubular portion 6 of the envelope by overlying the same adjacent the flange 20 against any possibility of arcing therewith.

While the envelope shown in Figure 1 may be formed without the double flanged portion 8 providing the annular opening 9 with the ceramic, this has been provided for the purpose of allowing air to pass through this annular opening 9 to insure rapid conduction of heat away from the ceramic, thereby maintaining the switch cool and increasing, to a great extent, the operating life thereof, as well as insuring positive repeat performance of the switch insofar as its operating angles are concerned.

It should be apparent that by designing a ceramic having the undercuts as defined by the grooves 17 and 18, an appreciably larger volume of mercury can be retained in contact with the electrode than was heretofore possible, while at the same time, due to the annular shape of the retaining chamber, any tilting movement will result in rapid movement of the mercury body 36 out of the grooves 17 and 18 and up along the face of the electrode 25 to protect this face and shield it against impingement from the mercury body 37.

Considering now the form of the invention shown in Figure 2, the metal envelope shell 40 is provided having the cylindrical body portion 42 provided with the integrally closed end 43. The opposite end of the shell is enlarged to form a cylindrical open end portion 44 joined to the body portion 42 by the frusto-conical shoulder 45. Disposed within the open end of the shell is a ceramic insert 46 having an inclined runway 47 terminating at its small end in a radial wall 48 which defines with the cylindrical bore 49 of the insert an annular groove or recess shouldered or counterbored to receive the annular projecting cylindrical flange 50 of an electrode 52. The electrode 52 closes the outer end of the bore 49 of the ceramic, and a suitable tubulation 53 is extended into the electrode and has the flange portion 54 welded to the inner face thereof to form a leak proof connection therewith.

To shield the face of the electrode 52 from direct impingement of mercury, a refractory 55 is provided held against the face by means of an annular retaining ring 56 which may be pressed or welded within the cylindrical projection 50 of the electrode. The refractory 55 is provided with an opening 57 providing com-

munication with the interior of the envelope 42. The tubulation 53 is preferably provided with a copper coating or sleeve 58 extending through the bore of the electrode 52 and providing for increased conductivity to provide a terminal connection to the electrode from the projecting end of the tubulation.

Suitable resilient sealing means 60 is adapted to engage the radial face of the electrode 52 around the sleeve 58 and tubulation 53, and is provided with a skirted portion 62 radially overlapping the electrode and a portion of the ceramic insert 46 to form a radial seal thereabout. The sealing means 60 is compressed into sealing engagement by means of a compression member 63 corresponding to the member 30 of Figure 1 having the reduced cylindrical extension 64 forming an insulating spacer about the projecting tubulation and sleeve. The compression member is held in position by spinning over the end 65 of the envelope 40 against a metal retaining ring 66.

Disposed within the switch envelope is a retained body of mercury 67 held in the annular groove formed by the radial shoulder 48, the bore 49 and skirt 50 of the electrode, and a movable body of mercury 68 carried in the tubular portion 42 of the envelope and adapted to move over the inclined surface 47 into and out of contact with the body of mercury 67.

Inasmuch as the inner face of the electrode 52 is shielded by the refractory 55, it is apparent that there can be no direct metal to mercury contact upon operation of the switch but that a true mercury to mercury contact will be effected at all times. Also, due to the relatively long skirt portion 50 on the electrode, it is obvious that an appreciable contact area is provided between a retained body 67 and the electrode sufficient to materially reduce the internal resistance of the switch.

The tubulation 53 is provided for introducing the mercury bodies into the switch envelope after which the tubulation is connected to a source of vacuum and the switch chamber is thereby evacuated and then filled with gas such as hydrogen under pressure after which the tubulation is pressed together and sealed as indicated at 69, similar to the manner described in connection with Figure 1. The copper sleeve 58 adds materially to the conductivity of the lead-out connection provided by the tubulation to insure reduction of internal resistance between the electrode and the terminal connection at the outer end of the tubulation. The structure shown provides a switch having a narrow operating angle, and it will be apparent that any arcs caused by making or breaking of the circuit through the switch will occur over the edge defined by the small end of the runway 41, and consequently will be spaced at an appreciable distance from any metal portion of the switch, these metal portions being thoroughly shielded by the mercury bodies so that there is no possibility of a metal to mercury contact. Due to the relatively large volume of mercury 67 in the retained body, it will be apparent that the same double run effect is produced, and that the two bodies of mercury move simultaneously upon opening of the circuit away from the sharp cutting edge provided at the inner end of the recess 47 and consequently insure breaking of the circuit at this point.

Considering now the form of the invention shown in Figures 3 to 6, inclusive, we have pro-

vided a switch structure incorporating the features of double run of the two bodies of mercury combined with the concept of increasing the volume of the retained body to an extent such that it will at all times mask the electrode face to prevent any metal to mercury contact.

In this form of the invention, the two-diameter metal envelope 70 has inserted therein the ceramic insert 72 provided with the radial shoulder portion 73 terminating the small diameter portion of the envelope. The insert is provided with a straight cylindrical bore 74 terminating at its inner end in the radial shoulder 75 and provided with the annular undercut groove 76 which is counterbored to receive the projecting cylindrical extension 77 of the electrode 78. Suitable sealing means 79 is provided for the outer radial face of the electrode 78 and the end of the ceramic, this sealing means radially overlapping a portion of the ceramic by reason of the skirted portion 80. The sealing means is retained in position by means of the compression member 82 held in position by the spun-over edge 83 of the envelope.

The envelope 70 is provided with the usual tubulation as previously described, and disposed within the undercut groove 76 and lying in the annular recess formed by this groove, the edge 75 and the base of the electrode, is a retained body of mercury 84 which, as will be apparent, has sufficient volume so that it contacts an appreciable portion of the inner face of the electrode 78. A movable body of mercury 85 is disposed in the tubular portion of the envelope and, as indicated in Figure 3, is dammed up against movement through the opening 74 by means of the radial shoulder 73. Upon tilting of the switch in the position shown in Figure 3, the movable body of mercury 85 piles up against the shoulder 73 until such time as a sufficient head is produced to break the surface tension and allow the upper stratum of the body of mercury 85 to rush through the opening 74 into contact with that portion of the body 84 lying in the opening 74 closing the switch circuit, as indicated in Figure 5. It will be apparent that by the time this occurs, the retained body 84 has moved over a sufficient portion of the face of the electrode 78 that no portion of the body 85 can contact the electrode portion 78, but a pure mercury to mercury contact is effected. From the position shown in Figure 5 the switch may be opened by tilting in the reverse direction, as indicated in Figure 4, causing the movable body of mercury 85 to move outwardly through the opening 74 at the same time that the retained body 84 is moving down into the well formed by the undercut 76 in the insert. As the two bodies of mercury tend to separate over the edge 75, the movable body 85 tends to move down into the closed end of the envelope, while the retained body 84 piles up in the well provided by the undercut and in the annular space between the edge 75 and the electrode face. Inasmuch as the undercut is annular in form, an appreciable volume of the mercury body 84 moves into the undercut, as indicated by the dotted line 86, showing the level of the mercury around the bore 74 within the undercut.

It is apparent therefore that with this type of switch, the two bodies of mercury both tend to move away from each other upon tilting of the switch toward open position, and the separation is effected about the edge 75 with both bodies moving away from this edge. As a result, a

double run action is provided, insuring positive breaking of the mercury circuit at a point removed from any metal portion of the switch structure. The provision of the radial shoulder 13 on the ceramic is of importance in insuring rapid movement of the movable body 85 through the bore 74 only after a predetermined mercury head has been built up, thus providing for a positive and snappy closing of the circuit, and eliminating any thin tongue of mercury running through the opening of insufficient section to carry the desired current. Preferably, the ceramic is provided with the externally carried seal 87 bearing against the shouldered portion of the envelope for preventing any portion of the mercury body 85 moving between the insert and the envelope wall. It will be apparent that with this construction, the bodies of mercury 84 and 85 approach equality, and that the volume of the body 84 is more than sufficient to shield the electrode face against any possibility of direct impingement thereon of the body 85.

In the embodiment of the invention shown in Figure 7, which is a combination of the features shown in Figures 2 and 3, the metal envelope 90 is provided with the enlarged cylindrical end portion 92 receiving the ceramic insert 93, this insert having the radial shoulder portion 94 and the annular undercut groove 95 defining an annular well with the flange portion 96 of the electrode 97. The electrode 97 is provided with suitable tubulation 98 for filling and evacuating the switch envelope, which tubulation is provided with a copper sleeve as described in connection with Figure 2. Sealing means 79 and 82 corresponding to that shown in Figure 3 is provided for the purpose of sealing the outer end of the envelope.

The opposite end of the envelope is provided with a tubular shell portion 99 having the re-entrant central cup portion 100 defining an axial recess 102 in the end of the switch, and thereby providing an annular torus or ring in which the movable body of mercury 103 is disposed. With this construction, rapid dissipation of heat from the metal envelope is provided due to the large surface thereof in contact with the air. The retained body of mercury 104 in the undercut portion of the ceramic is of sufficient volume due to its lying in an arcuate well to mask the face of the electrode 97 when the switch is tilted toward closed position. The straight through cylindrical opening 105 in the ceramic functions in the same manner as the opening 74 of Figure 3, and the operation of the switch through its various tilted positions is similar to that described in connection with Figures 3 to 6. However, by providing the movable body 103 in an arcuate position due to the reentrant portion 100 of the envelope, stability is provided, insuring positive operating angles for the switch structure. The skirt 96 of the electrode 97 is contacted by a sufficient volume of the retained body 104 to provide for small internal resistance in the switch, and the undercut 95 insures that the volume of mercury in the body 104 will be sufficient to provide the double run feature, as well as cool operation and masking of the electrode face to insure mercury to mercury contact, and also to insure that making and breaking of the circuit will be occasioned over a portion of the ceramic removed from any metal parts of the switch structure.

In Figures 8 and 9 we have provided a modified ceramic structure adapted to be incorporated in an envelope 70 corresponding to the envelope

of Figure 3. In this form of the invention the ceramic 110 is of generally cylindrical form having a frusto-conical inner portion 112 engaging the inner portion of the shoulder of the shell 70 and provided with the arcuately flared opening 113 terminating in a radially inwardly extending shoulder 114 which defines a cylindrical bore 115 through the ceramic. The bore 115 opens into an enlarged recessed portion 116 of the ceramic which is lined by the cylindrically flanged portion 117 of the electrode 118. Adjacent the bore 115 the ceramic is provided with axially outwardly extending finger portions 119. Preferably, four of such fingers are provided which extend to a point approximately $\frac{1}{2}$ " from the inner face of the electrode 118, as indicated by the dimension *a*; also the circumferential spacing between the fingers is approximately $\frac{1}{2}$ ", as indicated by the dimension *b*. The purpose of this spacing is to provide a stable retained body of mercury since we have found that a body of mercury confined within a cap of $\frac{1}{2}$ " or less possesses inherent stability, and by this construction it is apparent that the retained body of mercury 120 will be retained in stable position relative to the space between the fingers 119, as well as with re-space to the space between the ends of the fingers and the face of the electrode 118. The movable body of mercury 122 lying in the tubular end of the envelope is prevented by the shoulder 114 from dribbling through the opening 115 until such time as a sufficient head is built up to insure a flow of mercury through the opening of sufficient section to insure positive contact. As this mercury flows through the opening 115, it contacts the portion 121 of the retained body of mercury lying between the lowermost fingers 119 of the ceramic and the circuit is completed at this point and the movable body 122 never impinges upon any portion of the electrode 118. It will of course be apparent that when the switch is tilted toward switch closing position, the retained body 120 rises in the space between the lowermost fingers 119 and also along the face of the electrode 118, and consequently shields the electrode, as well as providing a stable mercury surface of considerable volume against which the lead edge of the mercury body 122 contacts. Thus, during making or breaking of the circuit through a switch of this type, any arcs will be formed adjacent the ceramic surfaces and removed from the metal surfaces of the envelope.

In the embodiment of the invention shown in Figure 10, a switch corresponding more or less to the type shown in Figure 2 is provided, with the exception that the ceramic insert 125 is provided with the outwardly curved opening 126 in the center thereof leading to the cylindrical bore 127. This switch is not provided with an undercut but merely has a mercury retaining well 128 formed in the ceramic with the body of mercury 129 lying therein in contact with the flange portion 130 of the electrode 132 and with a movable body 133 adapted to move up over the surface 126 and through the bore 127 into contact with the body of mercury 129. The body of mercury 129 is of sufficient volume, however, to insure that when a switch has been tilted to a point such that when the mercury 133 runs through the bore 127 the body of mercury 129 will be lying at a considerable angle in the well 128 such as to shield the face of the electrode 132 from a direct mercury contact, thus providing a mercury to mercury contact. The arcing that takes place will occur about the inner end of the

bore 127 which defines the well 128, and consequently will be removed an appreciable distance from any of the metal parts of the switch.

The switch shown in Figure 10 is provided with an insulating two piece case comprising a first case member 134 which encloses the metal shell 70 and extends axially at a distance therebeyond where it is engaged by the insulating cap member 135 suitably cemented to the end thereof. Such an insulating closure may be provided for all of the switches disclosed in the present application if so desired, and the defining junction between the pieces 134 and 135 may be suitably notched for leading out conductors 136 and 137 connected respectively to the shank of the electrode and to the metal retaining washer which is disposed in contact with the shell 70.

In the embodiment of the invention shown in Figure 11, a metal envelope 140 is provided having the radially enlarged cylindrical open end 142 within which is disposed the ceramic 143. This ceramic is provided with the frusto-conical bore 144 opening into a metal retaining well 145 defined annularly by the metallic flange portion 146 of the electrode 147 and carrying therein the retained body of mercury 148. A double flanged sealing member 149 is disposed in engagement with the radial outer faces of the electrode 147 and insert 143, the sealing means 149 having the forwardly extending peripheral flange 150 radially overlapping a portion of the ceramic insert 143 and having a rearwardly or outwardly extending skirt portion 152 which radially overlies a portion of the compression member 153. The shell is preferably beaded inwardly, as indicated at 154, to provide for radial compression of the sealing means intermediate the flanges 150 and 152, thereby insuring forcing of these flanges into tight compressive engagement between the internal walls of the extension 142 of the envelope and the ceramic pieces 143 and 153. This provides a very effective sealing means which cannot creep or flow during operation of the switch and which is augmented by the annular gasket seal 155 carried on the frusto-conical portion of the insert and engaging the shoulder portion 156 of the envelope. The electrode 147 has its radial inner face shielded by the ceramic 157 which is held in position by the ring 158 so that upon tilting of the switch, the radial face of the electrode is shielded against direct impingement of the movable body of mercury 159. Thus, a positive mercury to mercury contact is provided and the body of mercury 148 is of sufficient volume to insure low resistance contact with the flange portion 146 of the electrode, and also to produce the double run feature previously described.

In the modification of this structure shown in Figure 12, the electrode 147' has the ceramic disc 157' held in position by an internal bead 160 formed directly in the flange portion 146' of the cup-like electrode, whereby the use of an auxiliary retaining ring 158 is eliminated.

Considering now the form of the invention shown in Figure 13, a single diameter cup-shaped metal shell or envelope 162 is provided which is adapted to receive the insert 163, this insert being held axially in position within the open end of the envelope by providing an internal annular bead 164 providing a shoulder against which the ceramic is abutted. A frusto-conical gasket 165 which may be formed of any suitable material resistant to mercury is inserted between the inwardly extending end of the ceramic and the bead 164 to provide sealing engagement at 75

this point. A cup-shaped electrode 166 has its flange portion 167 centered in the cylindrical bore formed in the outer end of the ceramic 163, and defines the annular surface of the mercury retaining well in which the retained body of mercury 168 is disposed. The insert 163 has the radial inner face 169 forming a shoulder against which the movable body of mercury 170 abuts to build up a sufficient head for rapid movement of the mercury 170 into the bore or passageway 172 of the ceramic, as described in connection with the shoulder 73 of Figure 3. The body of mercury 168 being closely confined at the inner end of the passageway 172 rises along the inner face of the electrode 166 to shield the same from the movable body of mercury 170 when contact is made.

With this form of structure, it is apparent that the double drawing operations necessary for providing the two-diameter shells of previous forms of the invention, is eliminated and the internal shoulder desired for seating the ceramic against axial inward movement is provided by the annular bead 164. The ceramic is sealed against outward movement by means of the resilient sealing gasket 173 and the compression member 174 in the same manner as described in connection with Figures 1 and 2.

Considering now the modification of the invention shown in Figure 14, the switch envelope in this form of the invention is provided by using a straight tubular element 180, which is counterbored as at 182 to provide a shoulder for receiving the metal end plate 183 sealed in position by spinning over the end 184 of the tubular member. The end plate 183 carries suitable tubulation 185 for filling and evacuating the switch.

At its opposite end the member 180 is provided with a relatively long axially extending counterbored portion 186 forming the radial shoulder 187 adapted to receive the gasket 188 against which the ceramic insert 189 is disposed. The insert 189 is of simple form, having the radial internal shoulder portion 190 and the straight cylindrical bore 192 opening into a counterbored portion defined by the radial wall 193. A suitable cup-shaped electrode 194 is inserted into the counterbored portion and centered therein, the flange 195 of the electrode forming the annular lining of the mercury well in which the retained body of mercury 196 is disposed. A suitable sealing gasket 197 engages the radial outer face of the electrode 194, and has the skirt portion 198 radially overlapping the electrode and tapered to radially overlie the tapered end portion 199 of the ceramic. A suitable compression member 200 engages the outer face of the gasket 197 to compress the same into sealing engagement, and also compress the gasket 188 into sealing engagement. The compression member 200 is held in position by the spun-over edge 202 of the counterbored portion of the envelope 180. The movable body of mercury 203 is adapted to be dammed up by the shoulder 190 until a sufficient head is built up to allow it to snap through the opening 192 into contact with the retained body 196 which, at the same time rises radially inwardly along the face of the electrode 194 to shield the same from direct impingement of mercury thereon.

It is to be understood that in the forms of the invention shown in Figures 2, 10, 11, 13 and 14, the ceramic, if desired, may be provided with an undercut portion similar to that shown in

Figures 1, and 3 to 8 to provide the double run feature described in detail hereinbefore. Also, all forms of the invention may be enclosed within suitable insulating cases, as described in connection with Figure 10.

In Figure 15 we have disclosed a modified form of switch construction in which the envelope 42 corresponding to the switch envelope shown in Figure 2 is provided in the enlarged open end thereof with the insulator 205, which insulator is provided with a tapered runway 206 of relatively short axial length which, at its inner end is provided with the radial step or shoulder 207 for a purpose to be hereinafter described. The insulator 205 is also provided with the annular recess or circuit 208 extending annularly about the runway 206 and having radial communication through the radial gap 209 with the small end of the runway. Disposed in a shouldered bore communicating with the recess 208 and the radial gap 209 to form a radial closure for the outer end of the insulator is an electrode disc 210 having the projecting shank 212 extending axially outwardly of the open end of the envelope. The disc 210 is adapted to receive a baffle disc 213 which may comprise a metal such as tungsten, molybdenum, or any other similar metal having a far higher melting point, lower resistance, and higher conductivity than that of the iron forming the electrode. Molybdenum is preferred since it is slightly easier to machine and is less expensive. The disc is held in place by pressure between the ceramic shoulder and the iron electrode with the center of the disc being spot welded with nickel, as indicated at 214, to the electrode face.

The axial extent of the radial gap 209 is what may be termed "depth of electrode." The depth of the electrode in the form of the invention shown in Figure 15 has been determined by test to be most effective if maintained between $\frac{1}{16}$ " and $\frac{3}{32}$ ". The electrode and insulator are maintained in sealed relation in the end of the envelope by the sealing gasket 215 engaging the outer radial faces thereof and held in position by the compression member 217 corresponding to the compression members 30 and 63.

In the operation of the switch shown in Figure 15, upon tilting of the switch envelope in a counter-clockwise direction as viewed in the drawings, the main body of mercury 218 rolls to the left and encounters the stop or shoulder 207 which prevents its further movement until a sufficient head of mercury has been built up to run over the tapered runway 206. At the same time, the body of mercury 219 retained in the annular recess 208 and the radial gap 209 flows over the face of the disc 213, and consequently as the head of mercury from the body 218 breaks over the runway 206, it produces a positive mercury to mercury contact at the acute angle cutting edge 220 formed between the tapered runway 206 and the radial shoulder, which is spaced from the disc 213 to form the radial gap 209. Thus, there is no direct impingement of the mercury body 218 on the electrode disc. Similarly, when the circuit through the disc is to be broken, the switch is tilted in the opposite direction and the two bodies of mercury 218 and 219 run, respectively, out into the closed end of the shell 42 and into the recess 209, splitting over the cutting edge 220 whereby the movements of the two bodies of mercury are cumulative to increase the rate at which contact is broken in the switch and thereby minimize any arcing.

It is therefore believed apparent that we have provided a novel type of mercury switch structure having certain features which insure positive repeat performance and prevent any direct mercury to metal contact within the switch structure. At the same time, the structures are so designed as to insure that any arcs occurring within the switch will be spaced away from the metal parts of the structure which are adequately shielded therefrom. Also, we have provided simplified sealing means, and in certain forms of the invention, simplified envelope structures for insuring economy in manufacture.

We are aware that various changes may be made in certain of the details herein shown and described, and therefore, do not intend to be limited except as defined by the scope and spirit of the appended claims.

We claim:

1. A mercury switch comprising a cup-shaped metal envelope having an enlarged cylindrical open end, a ceramic insert seated in said end having a large cylindrical bore extending into the outer end thereof, means at the end of said envelope locking said insert against axial movement, a coaxial small cylindrical bore formed in the inner end thereof, said ceramic insert having an intermediate cylindrical flange portion between the bores providing for axial overlapping of said bores to define an annular axially extending recess about the inner bore, an electrode disc having a peripheral axial flange seated against axial movement in the outer end of said large bore with the flange forming at least a portion of the outer annular wall of said recess, the end of said intermediate ceramic flange terminating axially inwardly of the electrode face to form a radial gap therebetween opening radially outwardly into said recess, a first body of mercury in said envelope movable into said bore upon tilting of said switch in one direction, and a second body of mercury in said recess movable over the electrode face and said end of said bore upon said tilting to insure mercury to mercury contact.

2. The switch of claim 1 further characterized in that said recess defining means is provided with circumferentially spaced radial slots providing direct radial openings between said recess and the portion of said small bore intermediate the ends thereof, said openings and the said radial gap all being of a width not exceeding $\frac{7}{32}$ of an inch.

3. A mercury switch comprising a cup-shaped metal envelope having an enlarged open end, an insulator in said end having a radially inwardly directed shoulder at the inner end thereof, an axial bore in said insulator extending outwardly from said shoulder and terminating short of the outer radial face thereof, an enlarged bore in the outer end of said insulator and axially overlapping said first bore to provide an annular channel thereabout, a cup-shaped electrode closing the outer end of said enlarged bore and having the flange lying in said channel, bodies of mercury in said envelope and channel of substantially equal volume adapted to make and break contact over said terminating end of the first bore and axially spaced from said electrode face, and axially spaced sealing means between said insulator and envelope.

4. A mercury switch comprising a cup-shaped metal envelope having an enlarged open end, an insulator in said end having a radially inwardly directed shoulder at the inner end thereof, an

axial bore in said insulator extending outwardly from said shoulder and terminating short of the outer radial face thereof, an enlarged bore in the outer end of said insulator and axially overlapping said first bore to provide an annular channel thereabout, a cup-shaped electrode closing the outer end of said enlarged bore and having the flange lying in said channel, bodies of mercury in said envelope and channel of substantially equal volume adapted to make and break contact over said terminating end of the first bore and axially spaced from said electrode face, and a baffle disc lying over the face of said electrode within said flange.

5. A mercury switch comprising a cup-shaped metal envelope having an enlarged open end, an insulator in said end having a radially inwardly directed shoulder at the inner end thereof, an axial bore in said insulator extending outwardly from said shoulder and terminating short of the outer radial face thereof, an enlarged bore in the outer end of said insulator and axially overlapping said first bore to provide an annular channel thereabout, a cup-shaped electrode closing the outer end of said enlarged bore and having the flange lying in said channel, bodies of mercury in said envelope and channel of substantially equal volume adapted to make and break contact over said terminating end of the first bore and axially spaced from said electrode face, and an insulating disc secured over the face of said electrode.

6. A mercury switch comprising a cup-shaped metal envelope having an enlarged open end, an insulator in said end having a radially inwardly directed shoulder at the inner end thereof, an axial bore in said insulator extending outwardly from said shoulder and terminating short of the outer radial face thereof, an enlarged bore in the outer end of said insulator and axially overlapping said first bore to provide an annular channel thereabout, a cup-shaped electrode closing the outer end of said enlarged bore and having the flange lying in said channel, bodies of mercury in said envelope and channel of substantially equal volume adapted to make and break contact over said terminating end of the first bore and axially spaced from said electrode face, and a disc of a metal of the group consisting of tungsten, molybdenum or tantalum lying over the face of said electrode.

7. The switch of claim 3 further characterized in that said insulator has an annular groove formed in the lateral surface thereof adjacent the inner end adapted to support one of said sealing means.

8. A mercury switch comprising a cup-shaped metal envelope having an insulator secured in the open end thereof provided with an axial bore, a cup-shaped electrode carried in the outer end

of said insulator closing said bore, a resilient sealing disc having opposed axial flanges at the periphery thereof extending over the outer radial faces of said insulator with one of said flanges

5 radially overlapping said insulator, a compression member engaging the outer face of said disc, the other of said flanges radially overlapping said compression member, and an annular bead formed in said envelope intermediate said flanges.

10. In combination, a cup-shaped metal envelope having an annular internal bead formed adjacent the open end thereof, an insulator in said end, sealing means between said bead and insulator, an axial bore in said insulator, an electrode seated in the outer end of said insulator closing said bore, sealing means engaging the outer face of said electrode and insulator and radially overlapping said insulator, and means at the end of said envelope for axially compressing both said sealing means.

15. A mercury switch comprising an enclosing metal envelope having an insulator in one end thereof carrying an electrode, said insulator having means for retaining a body of mercury in contact with said electrode throughout normal operating movement of the switch, a second body of mercury in the envelope, said bodies making and breaking contact over a portion of said insulator spaced from said electrode, and a central 20 axially extending reentrant portion in one end of said envelope forming an annular recess exposed to outside air and terminating at its inner end adjacent said portion of said insulator.

25. A mercury switch comprising a cup-shaped metal envelope having an enlarged open end defined by a radial shoulder, an insulator in said end seated against said shoulder, an annular groove in the face of said insulator engaging said shoulder, sealing means in said groove, an 30 electrode carried by and closing the outer end of said insulator, a bore in said insulator providing communication between said envelope and electrode, sealing means engaging the outer radial faces of said electrode and insulator, and means 35 for axially compressing both said sealing means.

40. 12. The switch of claim 11 further characterized by the provision of an axially directed reentrant portion in said envelope at the junction of said body portion and shoulder adjacent said 45 first named sealing means and extending to a point adjacent said bore.

45. 13. The combination of claim 11 wherein said insulator has an annular recess radially spaced from said bore and opening toward said electrode, a body of mercury confined in said recess, and a second body of mercury movable through said bore to make and break contact with said first 50 body of mercury.
